Atty.*

Patented June 12, 1928.

Des. 75,510

UNITED STATES PATENT OFFICE.

JAMES F. MULHOLLAND, OF COLUMBUS, OHIO.

DESIGN FOR A TOY BALLOON.

Application filed March 28, 1928. Serial No. 26,053. Term of patent 3½ years.

To all whom it may concern:

Be it known that I, JAMES F. MULHOLLAND, a citizen of the United States, residing at Columbus, in the county of Franklin and State of Ohio, have invented a new, original, and ornamental Design for Toy Balloons, of which the following is a specification, reference being had to the accompanying drawing, forming part thereof.

The figure is a perspective view of a toy balloon showing my design.

I claim:—

The ornamental design for a toy balloon, as shown.

JAMES F. MULHOLLAND.
